US0D1107399S

(12) **United States Design Patent** (10) **Patent No.:** **US D1,107,399 S**
(45) **Date of Patent:** **** Dec. 30, 2025**

(54) **FOOTWEAR**

(71) Applicant: **Target Brands, Inc.**, Minneapolis, MN (US)

(72) Inventor: **Mariya Kroshinskaya**, Minneapolis, MN (US)

(73) Assignee: **Target Brands, Inc.**, Minneapolis, MN (US)

(**) Term: **15 Years**

(21) Appl. No.: **29/920,842**

(22) Filed: **Dec. 13, 2023**

Related U.S. Application Data

(62) Division of application No. 29/812,633, filed on Oct. 22, 2021, now Pat. No. Des. 1,013,349.

CLAIM

The ornamental design for a footwear as shown and described.

DESCRIPTION

FIG. 1 is a front, top, and left side perspective view of an embodiment of a footwear according to the new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a back, bottom, and right side perspective view thereof.

The broken lines in the drawings show portions that form no part of the claimed design.

1 Claim, 8 Drawing Sheets
